RUG MAKING

Howard L. Shuttleworth, Amsterdam, N. Y., assignor to Mohawk Carpet Mills, Inc., Amsterdam, N. Y., a corporation of New York

Application June 27, 1936, Serial No. 87,673

6 Claims. (Cl. 112—262)

This invention relates to pile surfaced rugs, such as are produced from a pile fabric woven in an indefinite length and subsequently cut into pieces of proper rug size, and is concerned more particularly with a novel binding or finish for the raw or cut edges of such a rug, and a method by which such binding or finish may be readily applied. The new binding not only improves the appearance of the edges along which it is used, but also prevents distortion and unraveling of the edge portions of the fabric and supports and protects the adjacent pile tufts against undue wear. It may be employed to advantage in connection with pile fabrics of various types, but since its use is especially desirable in the manufacture of rugs of Axminster fabrics, an adaptation of the invention for that purpose will be illustrated and described in detail for purposes of explanation. It is to be understood, however, and will be readily apparent that the utility of the invention is not limited to its employment on pile fabrics of any specific type.

In the production of Axminster rugs, it is now the common practice to weave an indefinite length of fabric which is made up of pile surfaced sections of final rug size connected by short lengths of web, referred to as headings, from which the pile tufts have been omitted. These rug sections are separated by cutting the headings transversely, and the rugs are then completed by finishing the raw or cut edges. For this purpose, the portion of the heading at each end of the rug is usually folded back underneath the body of the fabric and secured thereto by a hemming operation which involves stitching the inwardly folded edge to the main body of the fabric. In some instances, the raw edge of the heading is first bound by overedge stitching to the extent of about a half inch, the stitching being applied by a sewing machine and somewhat resembling the stitching employed in the binding of buttonholes. Regardless of whether or not the edge of the heading is thus bound, the folding under of the heading produces a double thickness of the web of the fabric adjacent the end edges of the rug, so that along these edges, the pile surface is raised somewhat, and as a result, is subjected to increased wear and crushing so that its appearance soon becomes impaired. Sometimes, in order to conceal the bent portion of the fabric, the line of bending is made to lie within the pile surfaced section a short distance, so that one or more rows of pile tufts are included in the bent portion. While this improves the initial appearance of the rug at its ends, the tufts referred to

are subjected to much wear, and as a result, they soon become matted and distorted and the edge becomes irregular and unattractive.

Another disadvantage of the present practice in the finishing of the raw or cut edges of such rugs is the result of the relatively loose weave of the fabric. Axminster fabrics are usually woven with stuffer and binder threads which are unsized and comparatively soft and the weft threads ordinarily employed are of unsized jute. This combination does not produce a tight bind in the web of the fabric, and although it is the common practice to coat the back of the fabric with a size to stiffen the web and bind the pile tufts in place, the web can be easily stretched and the weft threads moved out of alignment with one another. This is particularly true at any raw or unselvedged edge, and in the edge binding operation heretofore practiced, the stitches which attach the folded portion of the web to the main body portion of the rug extend parallel to the weft threads and consequently do not protect the edge portion from being distorted as a result of wear, handling, or other strains applied thereto. Such distortion of the fabric edges not only detracts from the appearance of the rug, but also permits the pile tufts along the edge to be loosened and dislodged.

The present invention is, accordingly, directed to the provision of a novel binding or finish for the edge of a pile surfaced rug, which avoids the disadvantages of the binding heretofore used, and also to a method by which the new binding may be readily applied. The binding of the invention does not increase the thickness of the body of the fabric to any important extent, it prevents undue wear of the pile tufts forming the face of the fabric along the bound edge, and it positively binds in place the threads in the body of the fabric for a considerable distance back from the edge so that raveling and pulling out of these threads and dislodgment of the pile tufts are avoided.

The new edge binding involves the use of a reinforcement which is applied to the back of the fabric along the edge thereof to be finished. This reinforcement may be of various materials, so long as it performs its desired function of securing the component parts of the fabric against relative displacement and it may conveniently take the form of a strip of thin textile material which is preferably adhesively affixed to the fabric with one edge of the strip aligned with the raw edge of the fabric. The strip has a width such that it engages a plurality of back weft threads and by reason of its being secured firmly

thereto, these weft threads are held securely in place and dislodgement thereof and distortion of the fabric are avoided. The raw edge of the fabric is then finished by overedge stitching which passes through the body of the fabric and the reinforcement, and the stitching is done in such manner that it embraces and encloses a plurality of weft threads in the fabric and at least one row of pile tufts. The bound portion 10 of the edge thus has considerable bulk and the stitching provides support for the row of pile tufts adjacent thereto, so that these tufts remain upright and do not become flattened or otherwise displaced.

15 For a better understanding of the invention, reference may be had to the accompanying drawing, in which

Figure 1 is a perspective view, partly in longitudinal section, illustrating a portion of a rug provided with the new binding, and

Figure 2 is a longitudinal sectional view of a portion of a pile fabric having its edge bound in accordance with the prior practice.

Referring to Figure 2, which illustrates one form of binding heretofore employed, the fabric shown therein comprises a web 10 having a pile surface formed of pile tufts 11. Beyond the end of the pile surfaced portion is a heading 12 which is a portion of the web of the fabric from which the pile tufts had been omitted during the weaving. To finish the rug, the heading is folded inward beneath the pile surfaced section, with the free end 13 of the heading having a further reverse fold, if desired. The folded portions are 35 then secured in place by a line of stitching 14 which passes through them and through the body of the fabric.

With the prior construction illustrated, it will be noted that when the rug lies flat on the floor, 40 the pile surface adjacent the line of folding 15 will be raised upward above the top of the remainder of the pile surface so that the tufts along the edge will be exposed to excessive wear. Also, the pile tufts 16, 17, and 18 adjacent the 45 line of folding are unsupported and they are bent downward in the folding operation so that they are subjected to the greatest wear during the use of the rug, and frequently become matted together or worn off. Moreover, the binding 50 operation does not hold together the weft threads in the folded portion at the left of the line of stitching, as illustrated in the drawing, and these threads, by reason of the excessive wear on the edge portions of the rug, become displaced, and 55 this promotes the loss of the tufts.

The binding of the invention is illustrated in Figure 1 in which it is shown applied to a rug of a typical Axminster fabric of the two-plane, three-shot construction. In this fabric, the weft shots 19, 20, and 21 lie above the upper stuffer warps 22, between the upper and lower stuffer warps 22, 23, and below the lower stuffer warps 23, respectively. The weft shots are bound in place by a single set of binder warps 24 and the tuft yarns 25 are looped about the middle weft shots 20.

In the production of rugs from this fabric, the fabric is woven in an indefinite length without headings and cut into pieces of rug size. Thereafter, the raw edges are finished by first applying a reinforcing strip 26 to the back of the fabric along each raw edge, and preferably with one edge 27 of the strip substantially aligned with the raw edge of the fabric. The reinforcing strip 75 may be of various materials, but it is preferably

of thin closely woven textile material and it is preferably secured in place by a film 28 of an adhesive, such as a plastic cement. An adhesive containing rubber is preferred by reason of its waterproof qualities, and preferably the adhesive 5 employed is one which is capable of setting quickly. The reinforcing strip is of a width such that it underlies a plurality of back weft shots 21, and in the fabric illustrated, the strip underlies five such shots, although a greater or less number may be engaged by the strip. Also in the drawing, the strip and the film of adhesive are shown somewhat enlarged, but it is to be understood that together they do not add materially to the thickness of the fabric. 10 15

To complete the binding, each raw edge of the fabric is enclosed by overedge stitching 29 which passes through the pile surface, the body of the fabric, and the strip 26, with the stitching enclosing a plurality of weft shots and at least one 20 row of pile tufts. In the construction illustrated, the stitches enclose four weft shots and one row of tufts 30, and the stitches lie close together and are drawn sufficiently taut to crush and compress the row of tufts enclosed by them. 25 The compressed tufts 30, together with the closely adjacent stitches which enclose and conceal them, produce an enlargement along the edge of the fabric which, as shown, is thicker than the body or web of the fabric and extends above it 30 and part way up the height of the pile surface. One portion 31 of each of the stitches lies in contact with the pile tufts 32 in the row lying next adjacent to the bound edge, and the enlargement supports these tufts 32 and prevents them from 35 being distorted and forced out of position when the rug is in use.

If desired, the strip 26 may be attached to the web before the roll of fabric is cut, and it may be coated with an adhesive and applied to the 40 back of the web by pressure or by heat, or the adhesive may be applied to the back of the web and the strip then affixed thereto.

It will be evident from the foregoing that the new binding is far superior to the binding now 45 in use in numerous respects. The reinforcement engaging the back weft shots prevents the fabric from becoming loosened and the weft shots separated and it also provides an anchorage for the overedge stitches. If no reinforcement were employed, the overedge stitches and the weft shots and pile tufts enclosed thereby would become loose in the course of time and might even pull off the binder and stuffer warps. With the overedge stitches passing through the 50 reinforcement and the latter secured to the back of the fabric over a substantial area thereof, the component parts of the fabric adjacent the edge are maintained firmly in position and the overedge stitches cannot be dislodged. The new 55 binding does not add sufficiently to the thickness of the fabric to cause excessive wear on the pile tufts adjacent the bound edge, and since the visible portion of the binding has considerable bulk by reason of the pile tufts enclosed 60 therein, the binding gives the rug an attractive appearance. The use of the new binding also effects a saving in manufacture, in that when the new binding is employed, the fabric may be woven in a continuous length, and it is not 65 necessary to weave headings between adjacent pile surfaced sections.

While I have described the new binding as applied to the transversely extending edge of an Axminster fabric, it will be evident that it 70 75

may be employed advantageously along any raw edge of any kind of pile fabric. It is particularly useful, however, in connection with Axminster fabrics because of the characteristics of 5 that weave.

I claim:

1. A rug which comprises a fabric body made up of interwoven warp and weft threads and having a back and a pile surface formed of pile 10 tufts, said body having a raw edge, a reinforcement affixed to the back of the body along said edge, and an enlargement along said edge thicker than the fabric body excluding the pile surface and formed of a plurality of closely adjacent overedge stitches along said edge passing 15 through the body and reinforcement and at least one row of pile tufts along said edge enclosed within and concealed and compressed by said stitches, said enlargement engaging and supporting the pile tufts adjacent thereto. 20

2. A rug which comprises a fabric body made up of interwoven warp and weft threads and having a back and a pile surface formed of pile tufts, said body having a raw edge, a reinforcement strip affixed to the back of the body along 25 said edge, and an enlargement along said edge thicker than the fabric body excluding the pile surface and formed of a plurality of closely adjacent overedge stitches along said edge passing 30 through the body and reinforcement and at least one row of pile tufts along said edge enclosed within and concealed and compressed by said stitches, said enlargement engaging and supporting the pile tufts adjacent thereto. 35

3. A rug which comprises a fabric body made up of interwoven warp and weft threads and having a back and a pile surface formed of pile tufts, said body having a raw edge, a reinforcement adhesively affixed to the back of the body 40 along said edge, and an enlargement along said edge thicker than the fabric body excluding the pile surface and formed of a plurality of closely adjacent overedge stitches along said edge passing through the body and reinforcement and at 45 least one row of pile tufts along said edge enclosed within and concealed and compressed by said stitches, said enlargement engaging and supporting the pile tufts adjacent thereto.

4. A rug which comprises a fabric body made 50 up of interwoven warp and weft threads and having a back and a pile surface formed of pile tufts, said body having a raw edge, a reinforcing strip affixed to the back of the body with one edge substantially in registry with said edge of 55 the body, and an enlargement along said edge thicker than the fabric body excluding the pile surface and formed of a plurality of closely adjacent overedge stitches along said edge passing through the body and strip and at least one row

of pile tufts along said edge enclosed within and concealed and compressed by said stitches, said enlargement engaging and supporting the pile tufts adjacent thereto.

5. A rug which comprises a fabric body made 5 up of interwoven warp and weft threads and having a back and a pile surface formed of pile tufts arranged in rows, said body having a raw edge, a strip of fabric affixed to the back of the fabric along said edge thereof by means of an 10 interposed film of plastic cement, and an enlargement along said edge thicker than the fabric body excluding the pile surface and formed of a plurality of closely adjacent overedge stitches along said edge passing through the body and 15 strip and at least one row of pile tufts along said edge enclosed within and concealed and compressed by said stitches, said enlargement engaging and supporting the pile tufts adjacent thereto. 20

6. A rug which comprises a fabric body made up of interwoven warp and weft threads and having a back and a pile surface formed of pile tufts, said body having a raw edge, means on 25 the back of the body along said edge for preventing relative dislodgment of the warp and weft threads, and an enlargement along said edge thicker than the fabric body excluding the pile surface and formed of a plurality of closely adjacent overedge stitches along said edge passing through the body and said means, and at 30 least one row of pile tufts along said edge enclosed within and concealed and compressed by said stitches, said enlargement engaging and supporting the pile tufts adjacent thereto. 35

7. A method of binding the raw edge of a pile fabric having a pile surface formed of rows of pile tufts, which comprises affixing a reinforcing strip to the back of the fabric along said edge, and passing a series of closely adjacent overedge 40 stitches through the fabric and strip along said raw edge with said stitches enclosing, compressing, and concealing at least one row of tufts, said stitches and compressed tufts forming an enlargement engaging and supporting the adjacent 45 tufts.

8. A method of producing pile surfaced rugs which comprises weaving a pile fabric in an indefinite length, the fabric having a pile surface throughout, severing pieces of rug size from the 50 fabric, applying a reinforcement to the back of the fabric adjacent each cut edge, and passing a series of closely adjacent overedge stitches through the fabric and reinforcement along each cut edge with said stitches enclosing, concealing 55 and compressing at least one row of tufts, said stitches and enclosed tufts forming an enlargement engaging and supporting the adjacent tufts.

HOWARD L. SHUTTLEWORTH.
